his attorney.

UNITED STATES PATENT OFFICE.

PETER W. BOLI, OF WILKINSBURG, PENNSYLVANIA.

PROPELLER MECHANISM FOR VESSELS.

Application filed June 13, 1924. Serial No. 719,727.

To all whom it may concern:

Be it known that I, PETER W. BOLI, a citizen of the United States, and residing in the borough of Wilkinsburg, in the county of Allegheny and State of Pennsylvania, have invented or discovered the new, useful, and Improved Propeller Mechanism for Vessels, of which the following is a specification.

My invention consists in new and improved propeller mechanism for vessels, and the same is particularly intended for light draft vessels on inland rivers.

In relatively shallow waters, marine screw propellers which are entirely, or almost entirely, immersed in the water, are not practical owing to their draught, and therefore the general practice has been to use paddle wheels, either side or stern, a more expensive construction and requiring more power to operate.

In some cases propellers have been used, the same being inclosed in a tunnel in the hull, but in such case there is a material loss of power, and the vessels cannot be readily backed nor do they easily respond to movements of the rudders.

In inland river work where an irregular channel must be followed, and more or less frequent landings, and stoppings, startings and backings must be accomplished, the items of ready response to the rudder and ease in backing are of vital importance. This is especially true in the case of tug and tow-boats, power barges and the like.

The object which I have in view is the provision of screw propeller mechanism, adapted for use in shallow waters, and which will be characterized by all of the advantages of the screw propeller as compared to the paddle wheel, and which will be conductive to the easy steering and backing of the vessel.

For this purpose I extend rearwardly from the stern of the vessel, above the water line, a power-driven shaft or shafts upon which are mounted in tandem and in spaced relation a plurality of propellers whose flukes are at least partially immersed in the water when below the shaft but are clear of the water as they rise toward the horizontal. I may provide a single shaft aligned with the longitudinal axis of the hull, in the case of a small or moderately powered vessel, but I prefer to provide two such shafts, one at each side of and parallel with said longitudinal axis.

The twin shaft installation not only adds to the speed and power, but also improves the steering, as one shaft may be idle while the other is driven to turn the boat on a short radius. By interposing a central shaft between the twin shafts above described, the power and speed may be still further increased.

As a convenient method of supporting the shaft or shafts I provide a frame extending rearwardly from the hull above the water line and comprising beams somewhat similar to the "cylinder beams" of a stern-wheel vessel, but preferably of greater length than the cylinder beams, the rear ends of said beams being connected by a cross beam by which are carried the bearings for the rear end or ends of the driving shaft or shafts. The super-structure of the vessel may be extended rearwardly over and be supported by the beams.

While my invention may be used on steam vessels, I have designed my invention with particular reference to vessels driven by internal combustion engines, such as Diesel engines, and I may provide an engine for each shaft with interposed clutch, and speed and reversing gears, to facilitate operation.

In the accompanying drawings, which are however merely intended to illustrate the best known to me practical embodiment of the principles of my invention without limiting the scope thereof to the construction shown, Fig. 1 is a side elevation, partially broken away in section, showing a vessel to which my invention has been applied; Fig. 2 is a sectional view taken along the line II—II in Fig. 1, and Fig. 3 is an enlarged detail showing the mounting of the propeller flukes on the shaft.

The following is a detailed description of the drawings.

A represents the hull of the vessel. B represents a pair of beams which extend rearwardly at either side of the hull above the water-line, much the same as do the cylinder beams upon which is mounted the paddle wheel of a stern-wheel vessel. The beams B extend rearwardly for a greater relative distance than cylinder beams, and at their rear ends said beams are connected by the cross beam C. The superstructure D of the vessel may be extended rearwardly over the beams.

E represents the driving shaft or shafts.

In the embodiment shown in the drawings two shafts are shown, one at either side of the longitudinal axis of the hull A. The rear ends of the shafts E are journaled in 5 bearings 1 carried by the cross-beam C, while said shafts extend forwardly through bearings 2 in the stern of the hull A, and are connected by clutch mechanism 3 and change speed and reverse gear mechanism 4 10 with the Diesel engines E. As indicated in dotted lines in Fig. 2 each shaft B is preferably provided with its own engine or engines.

The shafts E are above the water line, 15 which water line is indicated at G in Fig. 1.

Spaced along the shafts E are the propellers which may be of any suitable character. I have shown the same as of the twin blade 20 type, having the diametrically opposed flukes H which may be conveniently bolted to perimetral flanges 5 of hub-collars 6 which may be keyed or otherwise fixed on the shafts. The propellers are spaced apart 25 along the shafts sufficiently so as not to interfere with each other's action, and are trimmed in the proper relation so as to produce a substantially continuous thrust on the water.

The rudder or rudders I are set close to 30 the stern of the hull in advance of the front propellers.

It is evident that by the tandem arrangement of the plurality of propellers on a shaft which is above the water line I am 35 enabled to obtain the same and even greater power as could be obtained by an immersed marine propeller, and at the same time I adapt the propeller method of propulsion to shallow waters.

40 The propellers operate in open or unobstructed water, so that no power is dissipated against confining walls as is the case where the propellers work within a tunnel in the hull. Thus the full thrust of the propellers is exerted in forward travel and in 45 backing, and in twin or triple shaft installations I may use the propellers in turning in the same manner as the twin propellers of a marine vessel or the paddle wheels of a 50 side wheel vessel.

What I desire to claim is:—

1. In a screw propeller mechanism for 55 vessels, the combination with driving means mounted in the hull, of a horizontally disposed shaft extending rearwardly from the hull, means for imparting rotary motion in either direction to said shaft from said driving means, and a plurality of propellers mounted in tandem and in spaced relation to each other on said shaft, the propellers being 60 immersed below their axes only.

2. In screw propeller mechanism for 65 vessels, the combination with driving means mounted in the hull, of a horizontally disposed shaft extending rearwardly from the 70 hull, a plurality of propellers mounted in tandem and in spaced relation to each other on said shaft, the propellers being immersed below their axes only.

hull, said shaft being positioned above the water line, means for imparting rotary motion in either direction to said shaft from said driving means, and a plurality of propellers mounted in tandem and in spaced 75 relation to each other on said shaft, the propellers being immersed below their axes only.

3. In screw propeller mechanism for 80 vessels, the combination with driving means mounted in the hull, of a support extending rearwardly from the hull above the water line, a horizontally disposed shaft journaled longitudinally of said support, means for imparting rotary motion in either direction to said shaft from said driving means, and a 85 plurality of propellers mounted in tandem and in spaced relation to each other on said shaft, the propellers being immersed below their axes only.

4. In a screw propeller mechanism for 90 vessels, the combination with driving means mounted in the hull, of a support extending rearwardly from the hull above the water line, a horizontally disposed shaft mounted longitudinally of said support and having 95 its end portions journaled in bearings at the front and rear ends of said support, means for imparting rotary motion in either direction to said shaft from said driving means, and a plurality of propellers mounted in tandem 100 and in spaced relation to each other on said shaft, the propellers being immersed below their axes only.

5. In screw propeller mechanism for 105 vessels, the combination of a pair of horizontally disposed shafts extending rearwardly from the hull above the water line and in parallelism with the longitudinal axial line of the hull, a plurality of propellers mounted in tandem and in spaced relation to each other on said shafts the propellers being immersed below their axes only, and means mounted in the hull for independently imparting rotary movement in either direction to each of said shafts.

6. In screw propeller mechanism for 110 vessels, the combination of a pair of horizontally disposed shafts extending rearwardly from the hull above the water line and in parallelism with the longitudinal axial line of the hull, a plurality of propellers mounted in tandem and in spaced relation to each other on said shafts the propellers being immersed below their axes only, a separate driving means for each shaft, and means for imparting rotary motion in either direction to each shaft from its driving means.

7. In screw propeller mechanism for 115 vessels, the combination of a support extending rearwardly from the hull above the water line, a plurality of horizontally disposed shafts journaled longitudinally of 120 said support and in parallelism with the longitudinal axial line of the hull and hav- 125

- ing their end portions journaled in bearings at the front and rear of said support, a plurality of propellers mounted in tandem and in spaced relation to each other on said shafts the propellers being immersed below their axes only, driving means, and means whereby rotary motion in either direction may be independently imparted to each shaft from said driving means.
8. In screw propeller mechanism for vessels, the combination of a support extending rearwardly from the hull above the water line, a plurality of horizontally disposed shafts journaled longitudinally of said support and in parallelism with the longitudinal axial line of the hull and having their end portions journaled in bearings at the front and rear of said support, a plurality of propellers mounted in tandem and in spaced relation to each other on said shafts the propellers being immersed below their axes only, a separate driving means for each shaft, and means whereby rotary motion in either direction may be imparted to a shaft from its driving means.
9. In a vessel for use in shallow waters,
- the combination of driving means mounted in the hull, a horizontally disposed shaft extending rearwardly from the hull and above the water level, means for imparting rotary motion in either direction to said shaft from said driving means, a plurality of propellers mounted in tandem in spaced relation to each other on said shaft, the propellers being immersed below their axes only, and a steering rudder in advance of said propellers.
10. In a vessel for shallow waters, the combination of a pair of horizontally disposed shafts extending rearwardly from the hull above the water line and in parallelism with the longitudinal axial line of the hull, means mounted in the hull for driving said shafts independently in either direction, a plurality of propellers mounted in tandem and in spaced relation to each other on each of said shafts, the propellers being immersed below their axes only, and a steering rudder in advance of said propellers.

Signed at Pittsburgh, Pa. this 9th day of June, 1924.

PETER W. BOLI.
